Attorney.

UNITED STATES PATENT OFFICE

THOMAS McLAUGHLIN, OF BRISBANE, QUEENSLAND, AUSTRALIA

GOLF PRACTICE SET

Application filed November 20, 1929, Serial No. 408,429, and in Australia August 6, 1929.

The invention relates to an improved golf practice set, the object of which is to produce a portable device for practising purposes, whereby when the ball is struck by a golf club, it flies upwards, rotates and eventually returns to its normal position avoiding the trouble of searching for and replacing it.

The invention consists of a metal base plate 10 mounted upon which is a vertical standard preferably of octagonal or hexagonal section; attached to the standard by a sliding socket and set screw is a tubular horizontal arm, into the end of which is inserted a headed pin which is fastened in the tube by a split pin.

On to the pin is suspended a wire rod provided at its lower end with a horizontally disposed ring and its upper end with a hook 20 upon which is suspended by a thimble a flexible cord and a golf ball.

In order that the invention may be easily understood I will now refer to the accompanying drawings in which:—

25 Fig. 1 is a perspective side elevation.

Fig. 2, fragmentary side view of horizontal arm and pin to enlarged scale.

Fig. 3, view from underside of golf ball.

The reference letters indicate like parts in 30 all figures.

A is the metal standard fixed to a base plate B by a socket C, the end of the standard where fitting into the socket is rounded forming a shoulder, the rounded end is 35 threaded and the standard is firmly secured to the base plate by a nut D; b are holes in the base plate for screwing on to a heavy wooden block or on to a floor and b1 holes for spiking the base plate to the ground.

40 E is a socket slideable upon the standard A to any desired height, F a set screw for adjustably fixing the socket to the standard and F1 its handle.

45 G is the horizontal arm fitting into the socket E, into the free end of the horizontal arm is inserted a headed pin H fastened by a split pin I.

Pivottally suspended upon the pin H is a 50 wire rod J provided at its upper end with

a hook K and terminating with a horizontally disposed ring L.

Suspended by a cord M furnished with a thimble N is a golf ball O having on its underside a cup-shaped washer P, a knob Q on the end of the cord prevents the ball from falling off.

The device can be dismantled with ease and packed for transport in a small compass.

Slight modifications may be resorted to 30 without departing from the spirit or scope of the invention.

In using the device the horizontal arm is adjusted to allow the ball to rest upon the ground or slightly above it according to the 35 wish of the player, when the ball is struck by a golf club it flies upwards and swings around several times, the suspended wire rod preventing the ball diverting from a circular plane and any liability of the cord 70 twisting round the horizontal arm.

What I do claim as my invention and desire to secure by Letters Patent is:—

A golf practice set comprising a base plate provided with a socket, a vertical standard, 75 a sliding adjustable horizontal arm, means for fastening said arm to the standard, a wire rod provided with a hook at its top end and a ring at its bottom end pivotally suspended upon the horizontal arm, a golf ball provided with a cupped washer and a cord for suspending same from the hook on the wire rod as herein described.

In testimony whereof I have signed my name to this specification.

THOMAS McLAUGHLIN.
